KNITTING MACHINE

Arthur H. Adams, Jr., Newark, N. J., assignor to
 Colorspace Patent Corporation, Newark, N. J.,
 a corporation of New Jersey

Application March 19, 1942, Serial No. 435,340

7 Claims. (Cl. 66—125)

This invention relates to new and useful improvements in the art of knitting, and more particularly in machine knitting with polychrome yarn to produce predetermined patterns.

Heretofore, polychrome yarn, i. e., yarn having differently colored portions recurring in a definite sequence throughout its length, has been knitted by hand and by machine into fabrics displaying predictable patterns. In machine knitting, the position of a colored spot of the 10 yarn was checked at certain intervals by a photo-electric cell, and devices controlled by it varied the rate of yarn feed or the length of the stitches in accordance with the results of these intermittent checks. In hand knitting, each stitch was checked for color. Examples of such arrangements are disclosed in Patent No. 2,186,814 to A. H. Adams and Patent No. 2,228,633 to F. D. Leech.

Excellent as these methods are within their fields, I have found it impossible to apply them to knitting machines under human rather than electric eye control. The operation is too rapid for the eye to record at a particular interval of time or for each stitch the changes that occur, 25 and then effect the adjustment before the next interval arrives or the next stitch is formed. To do this, the machine would have to be slowed down to the pace of hand knitting.

It is the object of the present invention to make possible the knitting of polychrome yarn into fabrics having predetermined patterns by machines which function at much greater speeds than hand knitting and the adjustment of which is under the control of human operators.

Several arrangements for attaining this object are disclosed. One of the common characteristics of all these arrangements is that the operator's eye moves with the colored spots on the yarn while she is comparing these with a standard and that a relatively long stretch of yarn is compared with the standard. The human eye can do this even while the yarn moves rapidly and hence relatively high speed operation of the machine is made possible.

The invention will be described in greater detail in connection with the drawings in which Fig. 1 is a front elevation of a flat knitting machine;

Fig. 2 is a cross-section along lines 2'—2' of Figs. 1 and 3;

Fig. 3 is a plan view of the cams controlling the lift of the needles;

Fig. 4 is a front elevation of a modification of Fig. 1;

Fig. 5 is a top plan view of a circular knitting machine;

Fig. 6 is a cross-section along lines 6"—6" of Fig. 5; and

Fig. 7 is a cross-section along lines 7"—7" of Fig. 5.

The knitting machines per se are well known. In the drawings I show a Lamb flat knitting machine and a Griswold circular knitting machine, but the invention is applicable to machines of many other types. In the following I shall describe mainly the application of the present invention to these standard machines.

In Fig. 1, the yarn 1 passes from a supply (not shown) between yarn guides 2 and 3 provided on an upright 4 mounted on carriage 5 of the machine. The vertical stretch of yarn between 2 and 3 is long enough to include several color sequences which we shall assume consist of a succession of red, white and green spots, marked R, W and G.

A display board or easel 6 is mounted on legs 7 projecting from the base of the machine. The board is between the vertical length of yarn 2—3 and the post 4 and serves as a support for a vertical sheet serving as a color guide card 8. Marks in the form of stripes are painted on the card 8 corresponding in color and spacing to the colored spots on yarn 1, in the present case red, white and green. The stripes slope downward from the edge of the sheet towards the center. The width and slope of these stripes are such that as the yarn is moved longitudinally and transversely during the knitting operation, its colored spots will be always in alignment with correspondingly colored portions of card 8. Not all the colors need appear on this color guide.

In a flat knitting machine the lateral movement of the carriage 5 imparted to it through a rack and gear drive 11, 12 is approximately in proportion with the rate of yarn feed to the needles during the greater part of the knitting stroke. Since the yarn travels over a relatively long stretch (from several inches to several feet) between 2 and 3, and since this length of yarn moves with the carriage, the longitudinal and lateral movements of the length of yarn between 2 and 3 as related to the stationary background 8 will be resolved into a movement at an angle to the axis of the yarn. If, as in the present case, the yarn travels vertically between the guides, then its path with respect to the stationary background will be diagonal and this path is marked on 8 by the sloping stripes to afford the operator the opportunity of continuously check-

ing the colored spots on the yarn with respect thereto. Fig. 1 shows the yarn 2-3 and the post 4 moving from left to right.

The particular portion of the yarn that moves along a predetermined diagonal path will be knitted by a predetermined needle provided in the needle bed 10. If the rate of yarn feed relative to the transverse movement of the carriage 5 is increased, then a particular spot on the yarn will describe a path which forms a smaller angle with the axis of the yarn than the band of color marked on the background 8. If this ratio decreases then this angle will become larger. As the ratio keeps on increasing, the path of the colored spot will become more and more parallel with the yarn, and as it keeps on decreasing the two run more and more transverse to one another.

By regulating the size of the stitches, the operator may vary the rate of yarn feed and thus the relationship between the colored spots or any particular colored spot which she may be observing on the vertical stretch of yarn between points 2 and 3, and the diagonals or a particular diagonal on the background 8. As long as, say, a green spot stays within the limits of a green band, the rate of yarn feed will be correct for producing the desired color pattern in the fabric. If the color guide is marked with the red and white stripes also, then the position of any one of the colored spots may be checked.

The stitches are regulated by means of a large hand wheel 20 rotatably mounted on a shaft 21 projecting from carriage 5. A gear wheel 22 carried by shaft 21 and rotatable therewith is in mesh with a second gear wheel 23 (Fig. 3) rotatably mounted on carriage 5. The gear 23 rotates an eccentric 24 and the gear 22 an eccentric 25 which in the well known manner control the raising and lowering of cams 26 and 27 mounted on a cam plate 19. The longitudinal movement of the needles, e. g., 28 (Fig. 2) is determined by these two cams. When, as viewed in Fig. 3, the cams are traveling with the carriage from right-to-left, the left-hand edge of cam 27 will engage shoulder 29 on the needle and move it down slightly. From cam 27, the needle passes under the control of cam 30 which pushes it considerably above its original position. Then the needle is engaged by cam 26 which pulls it down again. This is the knitting stroke and it may be lengthened by moving the cam 26 down and shortened by moving it up. After it is released by cam 26 the needle rises again slightly to its original position.

When the cams travel in the opposite direction, then cam 27 performs the knitting stroke.

Since the length of yarn used up in a stitch varies with the length of the knitting stroke, the operator has in hand or hand-wheel 20 and the associated cams a readily available means for maintaining the colored spots on the yarn in registry or correspondence with the markings on 8 and thus insuring the knitting of a fabric having a predetermined color pattern.

If at the end of the travel of the carriage 5, from left-to-right as viewed in Fig. 3, a tab 31 projecting from a spring pressed movable plate 32 strikes a stop (not shown) then the machine will not knit during its movement in the opposite direction because this plate will cause cam 30 to rise so that the shoulders of the needles will pass under it. Then if at the end of the travel from right-to-left, 31 hits another stop, the ma-

chine will knit again from left-to-right on the next stroke.

The left-hand side of Fig. 2 illustrates the back of the machine which is identical with the front. If stops are suitably placed, the front and back of the machine will each knit in one direction only, producing circular knitting. It is sufficient in circular knitting if the length of the stitches is controlled during one-half of the travel since irregularities produced during the second half of the travel will not critically affect the color pattern.

If knitting is to be performed in both directions of travel, by the needles mounted in the front part of the carriage, then after one row or course of stitches is completed and the carriage 5 has reached its farthest position to the right (Fig. 1), then the color guide 8 is moved into another position on the easel 6, so that the colored spots on the yarn can be matched against a different set of colored stripes while the yarn travels from right-to-left. For each course, the matching with the left or right hand half of the color guide 8 and the lateral position of the guide depends on the color pattern desired in the fabric. To facilitate the positioning of the guide in accordance with the instructions, a fixed pointer 35 on the easel 6 cooperates with a scale 36 on guide 8.

In the modification shown in Fig. 4, the elements corresponding to those in Fig. 1 are indicated by corresponding primed reference numbers. Here a masking card 40 is placed over the color guide 8'. The mask 40 is provided with a longitudinal slot 41 in alignment with the yarn and through which a narrow strip of the color guide 8' is visible. The mask 40 is fastened to and moves with the carriage 5.

During the knitting operation, a red, white and green colored band will appear to be moving along slot 41 and the operator's duty will be to adjust the stitches so as to keep the colored spots on the yarn in step.

A similar effect is produced with the arrangement applied to the circular knitting machine disclosed in Figs. 5-7.

A band 50 dyed in the same manner as the yarn 51 is formed into an endless belt around two wheels 52 and 53. Wheel 52 is driven by a shaft 54 rotatably mounted in bearings 55 and 56. Bearing 55 is in a yoke 57 mounted on the base 58 of the knitting machine, and bearing 56 as well as the bearing 59 are mounted on a plate 60 fastened to yoke 57. The wheel 53 is rotatably mounted in bearing 59. The shaft 54 is driven by means of a chain 61 from the driving shaft 62 of the knitting machine.

The gearing between shaft 62 and the belt 50 is such that it will be driven at the same rate as the rate at which the yarn is pulled down by the needles 63. The operator will thus be enabled constantly to compare the color guide 50 with the long stretch of parallel yarn between eyelets 63, 64 for which it forms the background.

If the colored spots do not match, then adjustment is made by varying the stroke of the needles through the agency of cam 65. This is the cam which moves the needles 63 up and down in the needle cylinder 66. The cam 65 with its casing 67 is mounted on bevel gear 68 which surrounds the base of cylinder 66 and is driven by a bevel gear 69 fastened to shaft 62.

The cam 65 is raised or lowered by a ring 70 which surrounds the casing 67 and engages a projection 71 provided on the cam. The ring is screw-threaded as indicated at 72 and engages a

screw-thread 13 (Fig. 7) in bracket 14 and two other brackets mounted on base 58. By means of a handle or crank 75 the ring 70 is screwed in or out to move the cam 65 down or up. To give the operator convenient control of handle 15, a wheel 16 is rotatably mounted on an arm 11 of bracket 14. A finger 19 projecting from crank 75 engages a slot 18 (Fig. 5) in wheel 16 to transmit the rotary movement of wheel 16 to ring 70.

What I claim is:

1. In a knitting machine comprising needles for knitting polychrome yarn having a recurring sequence of colored spots into a fabric having a predetermined color pattern, a color guide adjacent the yarn and bearing visible elements corresponding to at least one of the colored spots on the yarn, means for moving the guide and the yarn with respect to one another so that said visible elements and the corresponding colored spots on the yarn will remain in correspondence with one another if the pattern is knitted as predetermined, and means for varying the size of the stitches to compensate for displacement of said corresponding spots on the yarn with respect to said visible elements.

2. In a knitting machine for knitting polychrome yarn into a fabric having a predetermined color pattern, a color guide against which a portion of the yarn may be viewed, means for moving the intersection of a visible element of the color guide with the yarn at the same rate as the predetermined rate at which the yarn must move to form the color pattern, and means for varying the size of the stitches being formed to compensate for differences between the two movements.

3. In a knitting machine for knitting polychrome yarn into a fabric having a predetermined color pattern, yarn guides for holding the yarn straight over a substantial length on its path towards the machine, a color guide against which the straight yarn may be viewed, means for moving the intersection of a visible element of the color guide with the yarn at the same rate as the predetermined rate at which the yarn must move to form the color pattern, and means for varying the size of the stitches being formed to compensate for differences between the two movements.

4. In a flat knitting machine for knitting polychrome yarn having a recurring sequence of colored spots into a fabric having predetermined color pattern, means including the needles of the machine for drawing yarn from a supply to form stitches, means for holding the yarn straight over a substantial length, a color guide adjacent said length of yarn and bearing visible elements corresponding to at least one of the colored spots on the yarn, said elements being in the form of at least one bar for a colored spot on the yarn and at an angle to the longitudinal

axis of the yarn, means for moving said length of yarn laterally with respect to said guide so that said stripe will remain in correspondence with the colored spot which it represents, and means for varying the size of the stitches to compensate for displacement of the corresponding spots on the yarn with respect to said bar.

5. In a flat knitting machine for knitting polychrome yarn into a fabric having a predetermined color pattern, yarn guides for holding the yarn straight over a substantial length on its path towards the machine, a color guide against which the straight yarn may be viewed, means for moving the intersection of a visible element of the color guide with the yarn at the same rate as the predetermined rate at which the yarn must move to form the color pattern, and means for varying the size of the stitches being formed to compensate for differences between the rate of movement of the yarn and its predetermined rate.

6. In a knitting machine comprising needles for knitting polychrome yarn having a recurring sequence of colored spots into a fabric having a predetermined color pattern, a color guide adjacent the yarn and bearing visible elements corresponding to at least one of the colored spots on the yarn, means for moving the guide and the yarn with respect to one another so that said visible elements and the corresponding colored spots on the yarn will remain in correspondence with one another, and means for varying the size of the stitches to compensate for displacement of said corresponding spots on the yarn with respect to the said visible elements including a cam for moving the needles, and a handle for varying the position of the cam relative to the needles.

7. In a flat knitting machine for knitting polychrome yarn having a recurring sequence of colored spots into a fabric having predetermined color pattern, means including the needles of the machine for drawing yarn from a supply to form stitches, means for holding the yarn vertical over a substantial length, a vertical sheet behind said length of yarn and bearing marks corresponding to at least one of the colored spots on the yarn, said marks being in the form of colored strips corresponding to the colored spots on the yarn and sloping down from one side of the sheet toward the other, the width of the stripe as measured along the yarn being the same as the length of the colored spot which it represents, means for moving said length of yarn laterally with respect to said sheet so that said stripes will remain in correspondence with the colored spots which they represent, and means for varying the size of the stitches to compensate for displacement of the spots on the yarn with respect to said stripes.

ARTHUR H. ADAMS, JR.
